UNITED STATES PATENT OFFICE.

JOHN HARTMAN, JR., OF PHILADELPHIA, PENNSYLVANIA.

CABLE-RAILWAY MECHANISM.

SPECIFICATION forming part of Letters Patent No. 421,494, dated February 18, 1890.

Application filed December 27, 1886. Serial No. 222,720. (No model.)

To all whom it may concern:

Be it known that I, JOHN HARTMAN, Jr., a citizen of the United States, residing at Philadelphia, in the county of Philadelphia and 5 State of Pennsylvania, have invented certain new and useful Improvements in Cable-Railway Grips; and I do hereby declare the following to be a sufficiently full, clear, and exact description thereof as to enable others 10 skilled in the art to make and use the said invention.

This invention relates to the cable railways for the transportation of passengers, and has for its object the easier engagement and disengagement of the gripping mechanism upon 15 the cable, the avoidance of shock in engaging and starting the car in motion, and the safe automatic disengagement of the grips at the points of intersection of such railways. 20 The nature of this invention may be briefly stated to consist of an improved gripping mechanism for engaging the cable, provided with a guiding mechanism to insure its safe passage through the conduit and the certain 25 re-engagement of the cable, an automatic disengaging device and guiding mechanism for intersections of cable roads, and an improved mode of attaching the gripping mechanism to the car to avoid the shock incident to suddenly gripping the cable, also a device for 30 clearing the slot from obstructions.

I will now proceed to particularly describe the mode of making and operating this invention, referring in so doing to the drawings annexed, and the letters of reference marked thereon, in which—

Figure 1 is a vertical lengthwise section of a car-truck and the portion of a cable railway at the intersection of a road containing 40 this invention. Fig. 2 is a vertical transverse section thereof. Fig. 3 is a plan view thereof. Fig. 4 is an enlarged vertical section of the gripping mechanism. Fig. 5 is a plan view showing the mode of attachment of the grip 45 to the car and the mechanism for operating the grip by hand; and Figs. 6, 7, and 8 are respectively a front elevation, a side elevation, and a vertical transverse section of a modified form of the gripping mechanism. 50 Figs. 9 and 10 are enlarged views of the gripping-jaws and wrist-plate, showing them in

different positions, with a cam formed on the hub of the said plate.

The same letters of reference apply to the same parts in the several figures.

55

C represents the chamber or space of the cable-conduit, having a slot c⁶ for the passage of the grip therein, and D D represent the tracks or rails for supporting the cars.

J is the cable located in the conduit C to 60 one side of the center and supported on grooved wheels K, turning upon spindles K'.

The gripping mechanism is attached to the car W, preferably to the axles or axle-boxes, as shown in Figs. 1, 2, 3, and 5, without the 65 intervention of the usual car-springs, so that the relative level of the rails and grip shall remain constantly the same, irrespective of the load on the car.

The gripping mechanism consists of two 70 jaws G² and G³. As shown in Fig. 4, these jaws are pivoted at G⁴ to a frame G⁵, attached to a flat shaft or plate G', extending upwardly and fitting loosely through the cleft C⁶ of the conduit C'. The jaw G² is pivotally connected at G⁶ by a link G¹⁰, attached pivotally to and operated by a wrist-plate G⁸, by the turning motion of which it is reciprocated to and from the cable J. The jaw G³, as shown 75 in Figs. 4, 9, and 10, rests against a cam G³⁴, 80 formed on the hub of the wrist-plate G⁸, and is moved to and from the cable J by the turning of the cam G³⁴ in an opposite direction to the motion of the jaw G². As shown in Fig. 8, the jaw G³, instead of being moved by a 85 cam, is moved by a link G', connecting it pivotally to the wrist-plate G⁸, and instead of being suspended upon the pivot G⁴ is attached by a pivot G⁹ to jaw G². To the wrist-plate is secured a chain G¹², attached thereto, as 90 shown in Figs. 4 and 8, connecting it to a vertically-moving slide G¹³. Upon the upper portion of the slide G¹³ is formed a shouldered projection or T-head G¹⁴, which fits in a correspondingly-shaped recess formed in a 95 toothed rack G¹⁵. The rack G¹⁵ is moved vertically by a pinion G¹⁶, having a feather or key G¹⁷, secured in the eye thereof, which fits so as to slide freely in a corresponding channel or key-seat G¹⁸ in the shaft G¹⁹, so that the 100 pinion G¹⁶ shall always turn with the shaft G¹⁹, although free to slide lengthwise there-

on. The plate G' is formed of two parts, between which the slide G¹³ is guided and moves freely in a vertical direction. The parts of the plate G' are united below by the frame G⁵ and above by the bearing G²⁰, secured thereto by shoulders fitting in corresponding notches and held therein by a latch G³³. The bearing G²⁰ is fitted so as to be supported by the shaft G¹⁹ and permit it to slide thereon. The shaft G¹⁹ is supported in bearings G²², having the spiral springs G³² placed between them and the bearings G²⁰ around the shaft G¹⁹. The bearings G²² are preferably made in one piece of metal with a frame G²³, which is supported by framing attached to the axle-boxes W'. This frame may be attached by boxes W², fitted upon journals W³, made specially therefor in the axles W⁴. The shaft G¹⁹ is provided with universal-joint couplings G²⁴ (see Fig. 1) and extends through bearings G²² to a convenient location for turning by means of toothed bevel-wheels G²⁶, connected to a windlass or lever G²⁷, having secured thereto a ratchet-wheel G²⁸, with which a pawl G²⁹ for holding it in position engages. Upon the frame G⁵ are rollers for guiding the cable in the gripping mechanism, so that it shall always be in proper position laterally to be engaged by the jaws G² and G³. These rollers may be either of grooved form or of cylindrical form, as desired. In the several figures of the drawings I have shown them as of both forms. They may be of tapering form, if desired, as shown, for the purpose herein stated. Attached to the wrist-plate G⁸ so as to turn or swing with it upon its fulcrum is a spindle G³⁰, having its axis in a plane at right angles to the line of the cable J and to the axis of the wrist-plate G⁸. This spindle G³⁰ is covered with rollers G³¹, and serves to raise the cable J into position to be gripped by the jaws G² and G³. The lower end of the frame G⁵, supporting the gripping-jaws, is guided by rollers G³⁶, which roll against the sides of the conduit C and prevent friction between the sides of the frame G⁵ and the sides of the conduit C, and are useful in supporting the grip laterally in passing curves. The rollers G³⁶ are tapered downwardly and act as a guide to the cable to prevent contact with the sides of the conduit and in directing the cable toward the space between the jaws G² and G³. A tapering inclined blade R is pivotally attached to the front of the grip-plate G' and serves to remove by lifting them any obstructions from the slot or cleft C⁶ in advance of the plate G', and by reason of the pivoted connection adapts itself readily to curves in the road. In the conduit C, near to the intersection of another conduit, are placed inclined guides, which raise the rollers G³¹, so as to clear the crossing cable J and the guiding-incline in the conduit. A roller K³, located near the intersection in one conduit, and under which the cable J of such conduit passes, serves to depress the cable, so as to clear the grips mov-

ing on the crossing cable. The grip attached to the lower cable, which cable passes under the upper cable, is automatically disengaged, at the approach to the intersection of the crossing, by a lever O striking a projection P in the road of the said lever, disengaging the jaws Q' and the clutch Q on the shaft G¹⁹.

In approaching a crossing of another cable the grip of cable must be released as the cable is depressed under the crossing cable. In order to make certain of the releasing of the grip, an automatic arrangement consisting of a clutch-lever O, whose fulcrum is above the clutch, and stop P, fastened on the upper side of the slot, is necessary, and is operated as follows: The lever, being held back as the car moves forward, disengages the clutch, which allows the shaft G¹⁹ to revolve, carrying the pinion engaging in the movable rack in connection with the slides G¹³, and releases the jaws, leaving the cable free, and the strain upon the cable draws it down, thus throwing the arm G³⁰ and rollers G³¹ down free from the cable and allowing the cable to pass freely by the rollers at the bottom of the conduit which supports the cable ahead of and behind the car. The arm or spindle G³⁰, hanging down as it nears the crossing, is brought in contact with the guard N', which is prolonged to and above the cross-cable, said arm G³⁰ being raised by the guard and carried over the cross-cable, when it falls down again in position to pass the cable-supporting rollers. The spring O² re-engages the clutch as soon as the lever O clears the stop P.

Having described my invention, what I claim is—

1. In a cable-railway grip, the combination of the jaws G² and G³ with the wrist-plate G⁸, rollers G³¹, and mechanism for operating said wrist-plate, substantially as set forth.
2. In a cable-railway grip, the combination of the pinion G¹⁶, arranged to slide upon the shaft G¹⁹, springs G³², and bearings G²⁰, arranged to operate substantially as set forth.
3. In a cable-gripping mechanism, the combination of the inclined guide N, rollers G³¹, wrist-plate G⁸, jaws G² and G³, with the cable J, roller K³, clutch Q, lever O, and projection P, arranged to operate substantially as and for the purpose set forth.
4. In a cable-railway gripping mechanism, the combination of the shaft G¹⁹, pinion G¹⁶, and bearings G²², supported inelastically from the axle-bearings and operated by a shaft provided with a universal joint, substantially as and for the purpose set forth.
5. The tapered rollers G³⁸, combined with the gripping-jaws G² and G³, and cable J, substantially as and for the purpose set forth.
6. In a cable-railway grip, the combination of the inclined blade R, pivotally connected to the plate G', and said plate G', as and for the purpose set forth.
7. In a cable-railway grip, the combination of the gripping-jaws, one jaw having a connecting-link pivoted thereto, with a wrist-

plate provided with a cam, the said connecting-link and wrist-plate adapted to operate together, substantially as shown and described.

5 8. In a cable-railway grip, the combination of the slide G¹⁸, having the T-shaped projection, with a toothed rack, the said T-shaped projection adapted to fit into a correspondingly-shaped recess formed in the said rack, substantially as and for the purpose set forth.

9. In a cable-railway gripping mechanism, the combination of the plate G', frame 5, bearing G²⁰, and the bearings G²² with the latch G³³, substantially as described, and for the purpose set forth.
